UNITED STATES PATENT OFFICE

2,611,108

ELECTRICAL LIGHTNING ARRESTER

Gösta Rydbeck, Västerås, Sweden, assignor to
 Allmanna Svenska Elektriska Aktiebolaget,
 Västerås, Sweden, a Swedish corporation

Application September 25, 1947, Serial No. 776,100
 In Sweden September 24, 1941

Section 1, Public Law 690, August 8, 1946
 Patent expires September 24, 1961

6 Claims. (Cl. 315—36)

1

In electrical lightning arresters with arc gaps connected in series with voltage dependent resistances, it has been proposed to shunt the resistances by capacities in order to decrease the voltage drop over the resistances caused by the charging current to the arc gaps. In this way any occurring over-voltage is distributed practically only over the arc gaps, so that the lightning arrester will function at a lower over-voltage than if a part of the over-voltage also is consumed as a voltage drop over the resistances.

In the case when the lightning arresters consist of a plurality of series-connected units of arc gaps or groups of arc gaps connected in series with resistances, it is important that all units should receive equally large parts of the over-voltage. For this purpose a capacitive potentiometer has been connected in parallel to the chain of arrester units, and the different units have then been connected with corresponding parts of the potentiometer. It is important that the capacities forming the capacitive potentiometer should be large in comparison to the capacity of the arc gaps and to their capacity to earth, because only in this case will the influence of the potentiometer on the voltage distribution over the arrester chain be dominant.

The carrying out of the two above-mentioned measures requires, however, the use of several comparatively large condensers, so that the arrester aggregate will occupy a considerable volume if condensers of the usual form are used.

The present invention has for its object an arrangement in which sufficiently large capacities can be arranged in the arrester in the manner indicated above without the volume of the arrester being increased to any great extent and without the height of it being greater, but instead the invention allows the arrester to be built very low.

According to the invention the arc gaps and resistances are arranged in piles side by side and in such manner that between the groups of arc gaps and between the different resistances insulating sheets are arranged, which also serve as condensers on the one hand for shunting the resistances and on the other hand for equalizing the voltage distribution over the units in the arrester chain. Metal coatings may be applied on the insulating sheets, so that they can at the same time serve as connections between the arc gaps and the resistances. It is thus suitable to make a part of the insulating sheets with their metal coatings long so that they project in between the units of the different piles. As they

2

reach from one pile to the adjacent pile, these will be connected with each other at the desired points.

The piles may suitably be arranged in the corners of a polygon corresponding to the number of piles, and the whole is suitably enclosed in an insulating container, for instance in a porcelain cylinder.

In the accompanying drawing,

10 Figure 1 shows a form of the invention. In this the spark gaps are arranged in a pile, and the resistances in two piles arranged on the side of the arc gap pile. In the drawing the piles are drawn side by side in spite of the fact that in reality they are arranged at the corners of a triangle.

Figure 2 shows diagrammatically the electrical connection of the different parts of the arrester.

In the drawing, 1 designates the electrode plates 20 of the arc gaps which are provided with a plurality of depressions and 2 are distance pieces inserted in these depressions between the electrode plates, which distance pieces are made of a suitable ceramic material containing silicium carbide or of a mixture of synthetic resin having a high carbon black content, with a high resistance and thus serve as voltage equalizing resistances. 3 are the voltage dependent resistances formed as cylinders of a ceramic resistance material such as silicium carbide and 4 and 5 are insulating sheets of mica or porcelain inserted between the resistance cylinders or between the groups of arc gaps. The insulating sheets 4 are connected with each other by means 30 of connections 6, whereas the insulating sheets 5, which are inserted between the groups of the arc gaps are so long that they reach in between the resistances. The insulating sheets 4 with their metal coatings will therefore form two parallel connected capacitive potentiometers, the parts of 35 which are connected with the arrester chain at corresponding points, whereas the insulating sheets 5 with their metal coatings form capacities which shunt the resistances 3. The different capacities are designated in Figure 2 by the same index as in Figure 1. By giving the insulating sheets a suitable thickness, the capacities of the potentiometer can be given the magnitude necessary to reach the desired distribution of the voltage.

40 The whole complex is enclosed in a porcelain cylinder 7 with a metal bottom 8. The cylinder 7 is closed at the upper end by a metal cover 9, and both the bottom and the cover are provided 45 with terminals (not shown). Between the cover

50 The whole complex is enclosed in a porcelain cylinder 7 with a metal bottom 8. The cylinder 7 is closed at the upper end by a metal cover 9, and both the bottom and the cover are provided with terminals (not shown). Between the cover

or the bottom and the outermost insulating sheets, yielding washers 10 and 11 are inserted, and the connection between the cover 9 and the bottom 8 with the beginning and the end of the arrester chain is performed by means of the connections 12 and 13.

The above described arrangement may of course be varied in many ways without departing from the invention. For instance the arc gaps and resistances may be arranged in one or more piles. The arrangement may also be such that the capacities shunting the resistances shunt these entirely, but it is also possible that only a part of the resistances are shunted. Further the capacities serving as potentiometer may be arranged either in one or more parallel-connected chains. It is further not necessary that the insulating sheets be provided with metal coatings, if the insulating sheets, nevertheless, will serve as condensers.

I claim as my invention:

1. A lightning arrester, comprising voltage dependent resistances, series-connected groups of arc gaps in series with said resistances, said resistances and arc gaps being disposed in columns arranged side by side, and condenser elements connected in parallel with said groups of gaps and resistances, said condenser elements consisting of insulating sheets having metal coatings on both sides providing electrical connection between the columns.

2. A lightning arrester, comprising voltage dependent resistances, series-connected groups of arc gaps in series with said resistances, said groups of arc gaps and voltage dependent resistances being arranged in parallel columns, condenser elements inserted in said columns and consisting of insulating sheets having metal coatings on both sides providing electrical connection between the columns, and metal connecting elements between said condenser elements and said groups of arc gaps and resistances and connecting said condenser elements in parallel with said arc gap resistance groups.

3. A lightning arrester comprising voltage dependent resistances, series-connected groups of arc gaps in series with said resistances, said arc gaps and voltage dependent resistances being piled up in parallel columns, condenser elements consisting of insulating sheets having metal coatings on both sides inserted in said columns, metal connecting elements between said condenser elements and said groups of arc gaps and resistances and connecting said condenser elements in

parallel with said arc gap resistance groups, and condenser members consisting of insulating sheets having metal coatings on both sides and being inserted in said columns and extending from one column to another, the coatings of said condenser members forming connections to connect said condenser elements in parallel with said voltage dependent resistances.

4. A lightning arrester comprising voltage dependent resistances and groups of arc gaps disposed in columns arranged side by side, and condenser elements consisting of insulating sheets having metal coatings on both sides inserted in said columns and providing electrical connection between adjacent columns.

5. A lightning arrester, comprising voltage dependent resistances and groups of arc gaps disposed in columns arranged side by side, condenser elements consisting of insulating sheets having metal coatings on both sides inserted in said columns and providing electrical connection between adjacent columns, and metal connections series connecting groups of said voltage dependent resistances and groups of said arc gaps in said columns.

6. A lightning arrester comprising a plurality of parallel columns of elements, one of said columns containing at least spark gaps and another containing at least voltage dependent resistances, means connecting elements of the columns in a series connection which includes alternately at least one resistance and at least one spark gap at adjacent levels in said columns, insulating members separating elements of said columns, said members having on both sides layers of conducting material, at least some of said members extending from column to column and the layers thereon forming a part of such series connection.
